METHOD OF AND APPARATUS FOR FORMING FRANGIBLE CASTING MOLDS

Lewis R. Schilling, Shaker Heights, Ohio, assignor to Kolcast Industries Inc., Cleveland, Ohio, a corporation of Ohio

Application September 1, 1954, Serial No. 453,613

20 Claims. (Cl. 22—31)

This invention relates to an improved method of forming frangible one-piece casting molds by making a fusible pattern which conforms to the article to be cast, investing the same in a suitable mold forming material, and fusing the pattern to remove it from the investing material and provide a casting cavity.

In forming molds by the investment method a pattern of fusible material is made that conforms accurately to the article to be cast and, in order to obtain a perfect casting, it is necessary to avoid distortion of the pattern during the assembly of the pattern parts and during investment of the pattern with the mold forming material and it is also necessary to prevent any marring of the investing material in the handling thereof incident to the fusion of the pattern and the discharge of the fusible material from the investing shell.

It is also important to effect a complete discharge of the material of the pattern from the interior of the mold forming shell, including any infusible substances which may be present in the material forming the fusible pattern.

In forming molds by the method of the present invention, a pattern composed of a low melting point material is accurately formed to a size and shape corresponding to that of the article to be cast and this pattern is supported during the investing and fusing operations by a carrier formed of a material of higher melting point than the pattern and rigidly attached to the pattern. The portion of the carrier attached to the pattern is provided with a covering layer of low melting point material that is integrally joined to the pattern by spaced gate forming risers of low melting point material that are integrally joined at one end to the pattern and at the other end to the covering layer on the carrier. After the pattern and carrier are assembled and joined together, the pattern and the portion of the carrier attached thereto are invested with a shell of the mold forming material, after which the investing layer is removed from the side of the attached part of the carrier that faces away from the pattern. After the shell is formed on the pattern and carrier the low melting point material within the shell is fused while the shell is supported with the carrier beneath the pattern so that the fusible material within the shell can be drained rapidly past the carrier to free the shell from the carrier and carry with it any infusible particles which may be mixed with the low melting point material employed in forming the pattern. The empty shell then provides a casting cavity in the portion thereof formed around the pattern, a recessed receiving portion for molten metal in the portion thereof formed about the carrier and spaced gates in the portion thereof formed around the risers that connect the recessed portion with the casting cavity.

The mold is preferably in the form of a relatively thin-walled shell of refractory material and this shell is formed on the pattern and carrier assembly by dipping the assembly in a ceramic paste of the proper consistency to form a relatively thin layer of ceramic material on the pattern,

2

risers and carrier. In order to form a more uniform coating, the pattern and carrier assembly may be dipped repeatedly in the ceramic paste and turned during the intervals between dipping. After the shell is freed from the pattern and carrier it may be inspected and repaired or reinforced by application of additional material to the exterior thereof if desirable and then baked at a high temperature to provide a refractory mold with a glazed or vitreous interior surface.

10 Various low melting point materials may be employed for the pattern, risers and carrier covering layer. Fusible waxes and plastic compositions that can be molded to the desired shapes and that have the requisite strength and various low melting point metals and alloys that have good casting characteristics may be employed.

15 The method of the present invention is particularly applicable to the making of molds for castings of intricate design which require patterns formed of a series of separately molded or cast sections such as molds for 20 turbine wheels. In forming patterns for such molds in accordance with the present invention, the portion of the pattern that conforms to the apertured peripheral portion of the wheel is made up of a series of castings, each conforming to an arcuate peripheral portion of the wheel 25 which includes one of the vanes. These castings each have arcuate outer portions that abut end to end to form a continuous peripheral rim and arcuate inner portions that abut end to end to form a continuous inner ring inwardly of the vanes. Each section has a vane that is 30 inclined with respect to the top and bottom faces of the section and that is integrally joined to the arcuate inner and outer portions of the section. In order to provide a firm weld between the sections, each section has end faces inclined in the same direction as the vanes, which 35 provide relatively large areas of contact between the ends of adjoining sections. The arcuate sections are welded together in an assembly rack by subjecting the end faces to be joined to heat sufficient to bring the surfaces close to the fusion temperature and pressing the abutting faces 40 together while the sections are held in proper relative positions in an arcuate channel. The assembly rack is formed with a circular channel in which the arcuate pattern sections have a sliding fit and the rack has a sector-shaped movable section which contains a part of the circular channel. The sections are joined end to end in the arcuate channel. A number of sections are first 45 joined together and placed in the movable sector which is supported in a retracted position, and the remainder 50 of the sections are then assembled in the stationary portion of the rack, after which the two sections of the rack are brought together to join the parts of the annulus carried by the two sections of the rack and complete the assembly of the arcuate sections in a closed annulus. 55 After the peripheral portion of the pattern is formed, a cast ring of the low melting point material conforming to the body portion of the wheel to be cast is welded to the inner ring of the annulus formed by joining the arcuate sections to complete the pattern.

60 The annular pattern so formed is attached to a carrier that has a ring-shaped attaching portion formed of a material of a melting point higher than that of the pattern and having a covering layer of low melting point material that has been applied thereto in a suitable manner such as by molding or casting. The risers connecting the pattern to the carrier may be cast integral with the pattern parts and these risers are preferably equiangularly spaced to form gates connecting the casting cavity to the annular pouring channel formed by the 65 investing material about the carrier.

70 Objects of the invention are to provide a method of forming molds by investment of a fusible pattern in

which the assembly and handling of the fusible pattern is simplified and in which the fusible pattern is protected against distortion during the pattern assembly and investment operations, to provide a method in which the pattern is fused and drained from the investing shell in such manner as to completely empty the shell and wash out any non-fusible residue which may be present in the material forming the pattern, to provide a method of assembling and joining pattern sections which insures a strong union between the sections and accurate conformity to the casting for which the mold is made, and to provide a method of forming a relatively thin walled refractory mold by the investment of a fusible pattern with ceramic material.

Reference should be had to the accompanying drawings forming a part of this specification, in which:

Figure 1 is a plan view of one of the molds for casting an arcuate pattern section, showing the hinged mold parts in closed position and the casing cavity in dotted lines;

Fig. 2 is a side elevation of the closed mold showing the mold cavity in dotted lines;

Figs. 3, 4, 5 and 6 are plan views of four differently shaped arcuate sections that are separately cast and that are joined together to form a part of a complete annular pattern;

Fig. 7 is a plan view of a ring-shaped casting that forms part of the completed pattern;

Fig. 25 is a section taken on the radial line indicated at 25-25 in Fig. 24; and

Fig. 26 is a section taken on the arcuate line indicated at 26-26 in Fig. 24.

In Figs. 3, 4, 5 and 6 of the accompanying drawings, castings 1, 2, 3 and 4 are shown, each of which conforms to an arcuate portion of a turbine wheel for which a mold is to be made. Each of these sections has arcuate inner and outer portions 5 and 6 that are connected by a thin vane 7. The vanes 7 of the sections 1, 2, 3 and 4 are all inclined in the same direction with respect to the bottom faces of the sections and the opposite ends of the inner arcuate portions 5 have inclined end faces 8 that are inclined in the same direction as the vanes 7. The outer arcuate portion 6 of each section has inclined end faces 9 that are disposed in the planes of the end faces 8 of the inner arcuate portion 5. The end faces 8 and 9 of each section are spaced from the vane 7 thereof and are adapted to contact throughout their entire extent with corresponding end faces of adjoining sections when the sections are assembled in the annular pattern.

The arcuate section 1 has a riser 11 projecting upwardly from its outer arcuate portion 6 and the sections 2, 3 and 4 have corresponding risers 12, 13 and 14. A suitable number of arcuate sections 1, 2, 3 and 4 are joined together to form the peripheral portion of an annular pattern which conforms to the apertured peripheral portion of the turbine wheel to be cast and the pattern also includes a ring 15 of low melting point material which conforms to the body portion of the turbine wheel. The ring 15 may be provided with circumferentially spaced risers 16.

Each of the arcuate pattern sections may be cast in a mold such as shown in Figs. 1 and 2, which has a base member 17 that has a flat bottom recess 18 with a circular peripheral wall 19 within which mold sections 20 and 21 have a sliding fit. The mold sections 20 and 21 swing on a central pivot 22 and meet on a radial parting line. The two sections of each mold have cavities 23 and 24 which conform to the arcuate portions 5 and 6 of one of the pattern sections and filler plates 25 and 26 mounted in these cavities provide core members between which the vane 7 of the section is formed. Each mold is provided with a pouring opening 27 and the two sections have handles 28 by means of which they can be moved to and from closed position.

As herein shown, the peripheral portion of the pattern is formed by fifteen arcuate sections. As shown in Fig. 12, the pattern annulus has three segments each consisting of two of the sections 1, a single section 2, a single section 3 and a single section 4. These fifteen sections are joined together to form the complete annulus in an assembly rack such as shown in Figs. 8 to 15 inclusive. As herein shown this assembly rack has a base plate 29 to which is permanently attached an assembly plate 30 which forms the major portion of a circular form for positioning the pattern sections. A radial track 31 is provided on the base plate 29 and a sector plate 32 is slidably mounted on the track 31. The stationary positioning plate 30 has a sector shaped recess to receive the sector plate 32 which engages the plate 30 on radial parting lines 33. A circular positioning channel 34 is formed in the plates 30 and 32 in which the arcuate sections 1, 2, 3 and 4 have a sliding fit. A positioning block 35 is detachably mounted on the base plate 29 when the sector plate 32 is in retracted position. The block 35 extends across an end of the channel 34 at one of the parting lines 33 and this block has an inner end portion that fits against the radial track 31 and is held in fixed position by suitable means such as a dowel pin 36. As shown in Fig. 8, the block 35 has a beveled face 37 against which the end faces 8 and 9 of the inner and outer arcuate portions of a pattern section fit.

In assembling the arcuate sections in the channel 34, one of the sections is placed in engagement with the beveled face 37 of the positioning block 35 and the other sections are then placed together end to end in abutting relation in the channel 34. Prior to assembly of the arcuate sections in the channel 34, the end faces of the sections are brought to a temperature near the fusion point so that the sections will be welded together when the inclined faces are pressed together. When the low melting point material of which the pattern sections are formed is mercury, a mercury amalgam, or a low melting point alloy containing mercury, the surfaces to be welded can be heated to the desired temperature by exposing them for a short period of time to air maintained at a temperature above the fusion point of the metal.

In forming an annulus from the arcuate sections, a sufficient number of the sections to fill the portions of the channel 34 in the sector plate 32 may be joined together in the channel of the stationary plate 30 and transferred to the sector plate 32, where they are supported as shown in Fig. 10 of the drawings. A sufficient number of sections may then be joined together in the portion of the channel 34 in the stationary plate 30 to fill the same, after which the sector plate 32 may be moved radially into engagement with the plate 30 to join the sections into a complete annulus, as shown in Fig. 12 of the drawings.

An inner circular positioning plate 38 is provided that has a beveled peripheral edge 39 that borders the inner side of the channel 34 and the inner arcuate portions 5 of the pattern sections have inclined shoulders 40 that fit on the beveled edge 39. The positioning plate 38 has a peripheral recess 41 in which the ring 15 fits and the ring 15 is provided on its under side with a V-shaped rib 42 that fits in the annular V-shaped channel formed by the beveled edge 39 of the positioning plate 38 and the inner faces of the arcuate portions 5 of the pattern sections. The sector plate 32 has an inner end face that engages the stationary plate 30 on a parting line 43 at right angles to the radial track 31, and the inner positioning plate 38 has a segment 44 thereof that is mounted on the sector plate 32.

After the arcuate sections have been assembled as shown in Fig. 12, the ring 15 is placed on the positioning plate 38 as shown in Figs. 14 and 15 and is welded to the inner ring of the annulus formed by the arcuate sections which it contacts throughout its circumference. The ring 15 and the annulus formed by the arcuate sections provide an annular pattern of low melting point material that conforms to the casting cavity that is to be formed in the mold.

In order to prevent distortion or marring of the pattern during the operations incident to the investment of the pattern with the mold forming material, the pattern is rigidly supported by a suitable carrier which also serves to form the pouring portion of the mold. As shown in Figs. 16, 17 and 18, the carrier has a rigid ring shaped attaching portion to which the pattern is joined, which may comprise inner and outer concentric rings 45 and 46 when the pattern has concentric rows of risers as herein illustrated. The inner ring 45 is of a size to overlie the risers 16 on the ring 15 and the outer ring 46 is of a size to overlie the risers 11, 12, 13 and 14 that are formed integrally with the arcuate sections of the pattern. The rings 45 and 46 are supported in concentric relation with their upper faces in the same plane by means of a framework which is formed by an annular row of posts 47 and 48 embedded in or otherwise attached at their lower ends to the rings 45 and 46, concentric metal rings 49 and 50 welded to the upper ends of the posts 47 and 48, and radial arms 51 welded to the top faces of the rings 49 and 50. The rings 45 and 46 and the framework supporting the same are formed of a metal of a higher melting point than the material forming the pattern. For example, the rings 45 and 46 may

be cast aluminum rings and the posts 47 and 48, rings 49 and 50 and arms 51 formed of steel. As shown in Fig. 16, three radial arms 51 are provided and these arms are equiangularly spaced, each arm projecting radially outwardly past the outer rings 50 and having downturned ends 52 which terminate in suspension eyes 53 adapted to receive the hooks of a suitable hoist. The eyes 53 are positioned below the top faces of the rings 45 and 46 to provide suspension points substantially in alignment with the center of gravity of the carrier and pattern assembly when the assembly is suspended from one or more of the eyes 53. In order to enable the carrier to be welded to the risers of the pattern, a covering layer 54 of fusible material may be formed on the rings 45 and 46 by casting or other suitable means.

The top faces of the risers 11, 12, 13 and 14 are made flat and lie in the same plane and the risers 16 also have flat top faces in a single plane, so that the low melting point covering material on the rings 45 and 46 has an adequate area of contact with the risers to provide a firm weld, securing the pattern to the carrier. After the pattern is attached to the carrier, the carrier and pattern assembly is suspended from a suitable hoist by engaging the hoist chain hooks to one or more of the suspension eyes 53 to support the pattern carrier assembly with the axis thereof substantially horizontal as shown in Fig. 19. So supported the carrier and pattern assembly is dipped in a ceramic paste bath of a consistency such that the ceramic material will adhere in a thin layer on the surfaces of the pattern and carrier. In order to obtain a coating of sufficient thickness to form a mold, the assembly is dipped several times in the ceramic paste and, in order to obtain a more uniform distribution of the ceramic material in the shell investing the pattern and carrier, turning movements may be imparted to the pattern carrier assembly between dippings. This turning movement may be imparted to the assembly by transferring the weight from a hoist chain attached to one carrier arm 51 to a hoist chain attached to another of the carrier arms.

After a shell of the desired thickness is obtained on the assembly, the ceramic material is removed from the flat sides of the rings 45 and 46 that face away from the pattern as shown in Fig. 20. The assembly is then supported on the carrier with the pattern above the carrier and while the assembly is supported in this position heat is applied to the low melting point material within the shell to fuse the same as shown in Fig. 21, the heat being applied to the exterior of the shell by placing the assembly in an atmosphere at a temperature above the melting point of the material forming the pattern and the covering layer on the carrier rings. This causes the portions of the fusible material contacting the interior of the shell to fuse first and, since the covering layer 54 is a relatively thin layer, the melting of this layer on the interior and exterior peripheries of the rings 45 and 46 opens channels for a drainage of the fused pattern forming material from the shell. As the pattern fuses the shell settles onto the rings 45 and 46 as shown in Fig. 21.

Any fused material trapped in the shell will flow out simultaneously throughout the circumference of the cavity formed by the pattern when the shell is lifted off the carrier. By reason of the free discharge of fused material, any infusible residue which may be mixed with the material forming the pattern will be washed out of the shell, leaving the interior of the shell free from any impurities which might cause imperfections in the interior surface of the shell upon subsequent baking thereof to form a refractory mold.

During the fusing of the pattern the shell is supported on the carrier by the portions thereof that are disposed between the risers, and the shell may be so supported while it is inspected and treated to repair any minor defects. The fusing of the pattern, risers and covering layer on the carrier rings frees the shell from the carrier

so that it can be lifted bodily off the carrier, after which it is baked at a high temperature to provide a refractory mold with smooth glazed or vitreous internal surfaces.

As shown in Figs. 22 and 23, the mold so formed has a mold cavity with circumferentially continuous inner and outer portions 56 and 57 which conform to the body and rim of the turbine wheel. The portions 56 and 57 are connected by narrow elongated passages 58 which conform to the vanes of the turbine. Above the casting cavity the mold has inner and outer circumferentially continuous pouring channels 59 and 60 which were formed about the carrier rings 45 and 46. The channel 59 is connected with the inner portion 56 of the casting cavity by gates 61 that were formed about the risers 16 of the pattern ring 15 about which the portion 56 of the mold cavity was formed. A pouring channel 60 is connected to the outer portion 57 of the casting cavity by circumferentially spaced gates 62 that were formed about the risers 11, 12, 13 and 14 extending upwardly from the portion of the pattern about which the portion 57 of the casting cavity was formed. In pouring the casting, molten metal may be simultaneously poured into the channels 59 and 60 to rapidly fill the circumferentially continuous portions 56 and 57 of the casting cavity and the metal from the portions 56 and 57 of the cavity will quickly fill the vane forming portions 58 of the casting cavity.

As shown in Figs. 24, 25 and 26, the resulting casting is a turbine wheel having a continuous annular body portion 63, a continuous annular rim portion 64 and thin inclined vanes of various lengths, thicknesses and contours.

While the invention is illustrated as applied to the production of an annular turbine wheel casting, it is to be understood that the invention is applicable to the production of other types of castings, particularly castings of intricate design requiring built up patterns. The design of the carrier and the arrangement of risers can be varied to accommodate the particular casting for which the mold is being made.

It is to be understood that in accordance with the provisions of the patent statutes, variations and modifications of the specific devices herein shown and described may be made without departing from the spirit of the invention.

What I claim is:

1. The herein described method of forming frangible refractory one piece casting molds which comprises forming a pattern of low melting point material, applying a covering layer of low melting point material on a carrier member that is of a size to overlie the major portion of one side of the pattern, joining said carrier to said pattern by means of spaced risers of low melting point material that are integrally joined to the pattern and to the covering layer on said carrier member, dipping said pattern and carrier member in a ceramic paste to invest the pattern and carrier in a shell of ceramic material, removing ceramic material from the side of the carrier member that faces away from the pattern, melting the material forming the pattern, the risers and the covering layer while the shell is supported with the carrier member below the pattern so as to drain the low melting point material past the carrier member and from the interior of the shell to free the shell from the carrier member, and baking said shell to form a frangible refractory mold having a casting cavity in the portion of the shell formed about the pattern, an open top pouring channel in the portion of the shell formed about the carrier member and gates connecting the pouring channel and casting cavity in the portion of the shell formed about the risers.

2. The herein described method of forming frangible refractory one piece casting molds which comprises forming a pattern of low melting point material, applying a covering layer of low melting point material on a carrier member that is of a size to overlie the major portion of

one side of the pattern, joining said carrier to said pattern by means of spaced risers of low melting point material that are integrally joined to the pattern and to the covering layer on said carrier member, supporting the pattern on the carrier, repeatedly dipping the carrier and pattern in a ceramic paste and imparting turning movements to the carrier and pattern between dippings to invest said pattern and carrier in a shell of ceramic material that is of substantially uniform thickness, removing ceramic material from the side of the carrier member that faces away from the pattern, melting the low melting point material while the pattern is supported on the carrier member and above the same to drain the fused material from the shell past said carrier member to free the shell from the carrier member, and baking said shell to form a frangible refractory mold having a casting cavity in the portion of the shell formed about the pattern, a pouring channel in the portion of the shell formed about the carrier member and gates connecting the pouring channel and casting cavity in the portion of the shell formed about the risers.

3. The herein described method of forming frangible molds for annular castings which comprises forming an annular pattern of low melting point material, applying a covering layer of low melting point material on a carrier ring that is composed of a material of higher melting point, attaching said carrier ring to said pattern in axially spaced substantially coaxial relation and interposing between the pattern and said covering layer a series of circumferentially spaced gate forming risers of low melting point material integrally joined to said pattern and said covering layer, investing the carrier ring and pattern in a shell of moldable hardenable heat resistant investing material, removing the investing material from the side of the carrier ring that faces away from the pattern, and melting the material forming the pattern, the risers and the ring covering layer while the shell is supported with the carrier ring below the pattern so as to drain the low melting point material past said ring and from the interior of the shell to free the shell from the carrier ring and provide a mold having an annular casting cavity in the portion of the shell formed about the pattern, an open top pouring annular channel in the portions of the shell formed about the carrier ring and gates connecting the pouring channel to the casting cavity in the portions of the shell formed about the risers.

4. The herein described method of forming frangible molds for annular castings which comprises forming an annular pattern of low melting point material that has integral circumferentially spaced risers projecting from one side thereof, applying a covering layer of low melting point material on a carrier ring that is composed of a material of higher melting point, attaching said carrier ring to said pattern in axially spaced coaxial relation by integrally joining said covering layer to said risers, investing the carrier ring, pattern and risers in a shell of moldable hardenable heat resistant investing material, removing the investing material from the side of the carrier ring that faces away from the pattern, and melting the material forming the pattern and said covering layer while the shell is supported with the carrier ring below the pattern so as to drain the low melting point material past said ring to free the shell from the carrier ring and provide a mold having an annular casting cavity, an open top annular pouring channel and circumferentially spaced gates connecting the pouring channel to the casting cavity.

5. The herein described method of forming frangible molds for annular castings which comprises forming an annular pattern of low melting point metal, applying a covering layer of low melting point metal on a carrier ring that is composed of a material of higher melting point, attaching said carrier ring to said pattern in axially spaced substantially coaxial relation and interposing between the pattern and said covering layer a series of circumferentially spaced gate forming risers of low melting point

metal integrally joined to said pattern and said covering layer, investing the carrier ring and attached pattern in a shell of moldable hardenable heat resistant investing material, removing the investing material from the side of the carrier ring that faces away from the pattern, and melting the metal forming the pattern, the risers and the carrier ring covering layer while the shell is supported with the carrier ring below the pattern so as to drain the low melting point metal past said ring and from the interior of the shell to free the shell from the carrier ring and provide a mold having an annular casting cavity in the portion of the shell formed about the pattern, an open top pouring channel in the portions of the shell formed about the carrier ring and gates connecting the pouring channel to the casting cavity in the portions of the shell formed about the risers.

6. The herein described method of forming frangible molds for annular castings which comprises forming an annular pattern of low melting point metal by casting a continuous ring and a series of arcuate sections and welding said arcuate sections end to end and to said ring, applying a covering layer of low melting point metal to a carrier ring of higher melting point, attaching the carrier ring to the pattern in axially spaced substantially coaxial relation and interposing between said pattern and said covering layer a series of circumferentially spaced gate forming risers of low melting point metal integrally joined to said pattern and to said covering layer, investing said carrier ring and pattern in a shell of moldable hardenable heat resistant material, removing the investing material from the side of the carrier ring that faces away from the pattern, and melting the metal forming the pattern, the risers and the carrier ring covering layer while supporting the shell with the carrier ring below the pattern so as to drain the low melting point metal from the shell past the carrier ring to free the carrier ring from the shell and form a mold having an annular casting cavity, an annular open top pouring channel and a series of circumferentially spaced gates connecting said pouring channel to said cavity.

7. The herein described method of forming frangible molds for annular castings which comprises forming an annular pattern of low melting point metal that has integral gate forming risers projecting from a side face and spaced apart circumferentially, casting a covering layer of low melting point metal on a carrier ring that is composed of a material of higher melting point and that is of a size to overlie said annular pattern, welding the metal covering layer on the inner side of said carrier ring to said risers, dipping said carrier ring and pattern in a ceramic paste to invest the same in a shell of ceramic material, removing the ceramic material from the outer side of said carrier ring, and melting the metal forming the pattern and the covering layer on the carrier ring while the shell with the pattern and carrier ring therein is supported with the carrier ring beneath the pattern so as to drain the low melting point metal past said ring and from the interior of said shell to free the shell from the carrier ring and provide a mold having an annular casting cavity in the portions of the shell formed about the pattern, an open top annular pouring channel in the portion of the shell formed about said carrier ring and a series of gates connecting the pouring channel and casting cavity in the portions of the shell formed about said risers.

8. The herein described method of forming frangible molds for annular castings which comprises forming an annular pattern of low melting point metal that has integral gate forming risers projecting from a side face and spaced apart circumferentially, casting a covering layer of low melting point metal on a carrier ring that is composed of a material of higher melting point and that is of a size to overlie said annular pattern, welding the metal covering layer on the inner side of said carrier ring to said risers, supporting said carrier ring and attached pattern with the ring axis substantially horizontal,

intermittently dipping said ring and pattern in a ceramic paste bath to cause the ceramic material to adhere thereto and form an enclosing ceramic shell, imparting turning movements to said ring and pattern about the axis of the ring between dippings to cause a more uniform distribution of the ceramic material in the shell, removing the ceramic material from the outer side of the carrier ring, and melting the metal forming the pattern and the carrier ring covering while the shell is supported with the carrier ring beneath the pattern so as to drain the low melting point metal past said carrier ring and from the interior of said shell and provide a mold having an annular casting cavity, an open top annular pouring channel overlying the casting cavity and a series of gates connecting said channel to said cavity.

9. The herein described method of forming frangible molds for annular castings which comprises forming an annular pattern of a low melting point metal that has inner and outer substantially concentric circumferential rows of integral risers projecting from one side face thereof, casting covering layers of a low melting point metal on two carrier rings formed of a material of higher melting point, one of a size to overlie one row of risers and the other of a size to overlie the other row of risers, welding the covering layers on the inner sides of said carrier rings to said rows of risers, dipping said carrier rings and the attached pattern in a ceramic paste to invest the carrier rings and pattern in a shell of ceramic material, removing the ceramic material from the outer sides of said rings, and melting the metal forming the pattern and the ring covering layers while supporting the shell with the carrier rings beneath the pattern so as to drain the metal from the interior of the shell past said rings to free the shell from said rings and form a mold having an annular casting cavity and two inner and outer annular pouring channels overlying the cavity and connected by gates to the cavity.

10. The herein described method of forming frangible molds for annular castings which comprises forming an annular pattern of a low melting point metal that has inner and outer substantially concentric circumferential rows of integral risers projecting from one side face thereof, casting covering layers of a low melting point metal on two carrier rings formed of a material of higher melting point, one of a size to overlie one row of risers and the other of a size to overlie the other row of risers, welding the covering layers on the inner sides of said carrier rings to said rows of risers, supporting said carrier rings with the pattern attached thereto with the axis of the rings substantially horizontal, dipping the rings and attached pattern while so supported repeatedly in a ceramic paste bath and imparting turning movements about said axis between dipping operations to form a ceramic shell about said pattern and rings, removing the ceramic material from the outer side of said rings, melting the metal of the pattern and carrier ring covering while the shell is supported with the carrier rings beneath the pattern to drain the metal from the shell past said carrier rings to free the rings from the shell to provide in the shell an annular casting cavity, a pair of annular pouring channels overlying the cavity and connected thereto by spaced gates, and baking said shell to provide a refractory mold.

11. The herein described method of forming frangible refractory one piece casting molds which comprises casting a series of pattern sections each composed of a low melting point metal and certain of the sections having integral risers projecting therefrom, welding said sections together to form a pattern with a series of risers projecting from one side thereof, casting a covering layer of low melting point metal on a carrier member composed of a metal of a melting point higher than that of the pattern and of a size to overlie said risers, welding said covering layer to said risers to attach the pattern

to the carrier, dipping said pattern and carrier member in a ceramic paste to invest the pattern and carrier member in a shell of ceramic material, removing the ceramic material from the side of the carrier member facing away from the pattern, melting the metal forming the pattern, risers and covering layer while the shell is supported with the carrier member beneath the pattern so as to drain the fused metal from the shell past said carrier member to free the shell from the carrier member, and baking said shell to form a frangible refractory mold having a casting cavity in the portions thereof formed about the pattern, a pouring channel in the portions thereof formed about the carrier member and gates connecting the pouring channel to the casting cavity in the portions thereof formed about the risers.

12. The herein described method of forming frangible refractory one piece casting molds which comprises casting a series of pattern sections each composed of a low melting point material, said sections having end faces inclined to the upper and lower sides of the sections and risers projecting from their upper sides, welding the sections together to form the pattern by heating the inclined faces to near the fusion point of the material and pressing the inclined faces together, casting a covering layer of low melting point material on a carrier member of a size to overlie said risers and welding and attaching said carrier member to the pattern by welding said covering layer to said risers, dipping the pattern and carrier member in a ceramic paste to invest the same in a shell of ceramic material, removing the ceramic material from the side of the carrier member facing away from the pattern, supporting the shell with the carrier member beneath the pattern and melting the material of the pattern, the risers and the covering layer to drain the material from the shell and free the shell from the carrier member, and baking said shell.

13. The herein described method of forming frangible molds for annular castings which comprises forming an annular pattern by casting a low melting point metal to form a series of sections that conform to arcs of an annulus, casting a circumferentially continuous ring with spaced gate forming risers projecting from a face thereof, welding said sections together end to end and to said annulus to form a pattern, casting a covering of low melting point metal on a carrier ring formed of material of a higher melting point and that is of a size to overlie said risers, welding the covering layer on the inner side of said carrier ring to said risers to attach said carrier ring to said pattern, dipping said carrier ring and pattern in a ceramic paste to invest the same in a shell of ceramic material, removing the ceramic material from the outer side of said carrier ring, and melting the metal forming the pattern and carrier ring covering layer while said shell is supported with the carrier ring on the under side thereof so as to drain the metal from the interior of the shell past said carrier ring to free the shell from said ring and provide a mold having an annular casting cavity in the portions of the shell formed about said pattern, an open top annular pouring channel in the portions of the shell formed about the carrier ring and a series of gates from said pouring channel to said cavity in the portions of the shell formed about said risers.

14. The herein described method of forming a mold for a turbine wheel or the like that has passages closely spaced circumferentially adjacent its periphery that extend therethrough at an inclination to the plane of the wheel and that are separated by thin inclined vanes which comprises forming an annular pattern of a low melting point metal which conforms to the apertured peripheral portion of the turbine wheel and which has circumferentially spaced gate forming risers projecting from one side face, applying a covering layer of low melting point metal to a carrier ring of a metal of higher melting point and welding the covering layer on the inner side face of

said ring to said risers, dipping said carrier ring and pattern in a ceramic paste to invest the same in a shell of ceramic material, removing the ceramic material from the outer face of said ring, and melting the pattern and carrier ring covering layer while said shell is supported with the carrier ring on the under side thereof so as to drain the metal past the carrier ring and from the interior of the shell to free the shell from said ring and provide a mold having an annular casting cavity in the portion of the shell formed about said pattern, an open top annular pouring channel in the portion of the shell formed about said carrier ring and a series of gates formed by portions of the shell formed about said risers and connecting said pouring channel and said cavity.

15. The herein described method of forming a mold for a turbine wheel or the like that has a circumferentially continuous peripheral portion and passages therethrough adjacent the periphery that are inclined to the plane of the wheel and that are separated by thin inclined vanes which comprises forming an annular pattern of a low melting point metal that conforms to the apertured peripheral portion and to the body of the wheel inwardly of the vanes and having circumferentially spaced gate forming risers projecting from a side face thereof casting a covering layer of low melting point metal on a carrier ring formed of material having a higher melting point and that is of a size to overlie said risers, welding the inner face of said carrier to said risers, dipping said carrier ring and pattern in a ceramic paste to invest the same in a shell of ceramic material, removing ceramic material from the outer face of said ring, supporting said pattern carrier ring and shell with the carrier ring on the under side, melting the metal forming the pattern and the carrier ring covering and draining the metal from the shell past said carrier ring to free the shell from the carrier ring and to form a mold having an annular casting cavity, a circumferentially continuous pouring channel overlying the cavity and a series of circumferentially spaced gates connecting said channel to said casting cavity.

16. The herein described method of forming a mold for a turbine wheel or the like that has a circumferentially continuous peripheral portion and passages therethrough adjacent the periphery that are inclined to the plane of the wheel and that are separated by thin inclined vanes which comprises forming an annular pattern conforming to the peripheral vane portion of the wheel and having an inner circumferentially continuous portion conforming to the body of the wheel inwardly of the vanes and having inner and outer rows of circumferentially spaced risers projecting laterally in the same direction from said inner and peripheral portions, casting a covering coating of low melting point metal on two carrier rings one of a size to overlie the risers of the outer row and the other of a size to overlie the risers of the inner row, welding the covering on the inner sides of one carrier ring to the risers of the outer row, welding the covering on the inner side of the other carrier row to the risers of the inner ring, dipping the carrier rings with the attached pattern in a ceramic paste to form a shell of ceramic material enclosing the carrier rings and pattern, melting the metal of the pattern and carrier ring coverings while the shell is supported with the carrier rings beneath the pattern so as to drain the metal from the shell and past the carrier rings to free the rings and form a mold having an annular casting cavity and two annular pouring channels overlying the cavity and connected thereto by spaced gates.

17. A carrier for supporting an annular pattern of low melting point metal for dipping in a bath of shell forming material comprising a cast metal ring, a series of axially extending metal posts having their inner ends attached at circumferentially spaced points to said cast metal ring, a metal supporting ring welded to said posts

and disposed substantially parallel to said cast metal ring, and equiangularly spaced arms welded to said supporting ring, said arms extending radially and having end portions bent toward the plane of said cast metal ring and terminating in suspension eyes radially outwardly of said cast metal ring.

18. A carrier for supporting an annular pattern of low melting point metal for dipping in a bath of shell forming material comprising two substantially coaxial cast metal rings disposed one within the other in radially spaced relation with their outer faces in substantially the same plane, circumferentially spaced metal posts having their inner ends attached to said rings and projecting axially outwardly therefrom, a metal supporting ring welded to the posts of each of said cast metal rings, said supporting rings being concentric and spaced outwardly from the outer faces of said cast metal rings, and equiangularly spaced radially disposed metal arms each welded to both of said steel rings and having outer ends bent inwardly and terminating in suspension eyes inwardly of said outer faces and spaced radially outwardly of said cast metal rings.

19. Apparatus for assembling arcuate sections end to end to form a closed annulus comprising a support having a top face provided with an open top circular channel of uniform width and depth throughout in which the sections to be joined have a sliding fit, said support having a fixed section and a movable section, said movable section being sector shaped and mounted for movement radially toward and away from the fixed section, said sections having radial parting lines that cross said channel, a positioning member engageable with said fixed section at one of the parting lines when the movable section is retracted and serving as a stop against which one of the arcuate sections to be joined may be engaged, said positioning member being removable to permit movement of the movable section into engagement with the fixed section and transfer of a series of joined arcuate annulus sections to the movable member and movement of the movable section into engagement with the fixed section to join annulus sections assembled in the portions of the circular channel in the fixed and movable support sections to form a complete closed annulus.

20. Apparatus for assembling in a closed annulus a

series of arcuate sections of uniform radial width and having flat end faces that abut and that are all disposed at the same inclination to their bottom faces, a support having a top face provided with an open top circular channel in which said arcuate sections have a sliding fit, said support having a fixed section and a movable section that is sector shaped and that is movable radially toward and away from the fixed section, said movable section engaging said fixed section on radial parting lines that cross said channel, a positioning member engageable with the fixed support section at one of said parting lines and having an inclined face against which an inclined end face of an arcuate annulus section will fit, said positioning member being removable to permit movement of the movable support member into and out of engagement with the fixed support member to permit transfer of a sufficient number of joined arcuate sections to fill the portion of the channel in said movable support member and to permit movement of the movable support section into engagement with the fixed support section to join arcuate assemblies of annulus sections on the two supports to form a closed annulus.
